(57) **CLAIM**

The ornamental design for a magnetic bottle or can opener holder, as shown and described.

DESCRIPTION

FIG. 1 is a front and top perspective view of a magnetic bottle or can opener holder in accordance with my new design;

FIG. 2 is a front elevational view thereof;

FIG. 3 is a rear elevational view thereof;

FIG. 4 is right-side elevational view thereof;

FIG. 5 is left-side elevational view thereof;

FIG. 6 is a top plan view thereof; and,

FIG. 7 is a bottom plan view thereof.

The broken lines in the figures are directed to environment and are for illustrative purposes only; the broken lines form no part of the claimed design.

1 Claim, 7 Drawing Sheets
